(57) **CLAIM**

The ornamental design for trousers, as shown and described.

DESCRIPTION

FIG. 1 is a rear, top perspective view of trousers, showing my new design;

FIG. 2 is another rear, top perspective view thereof;

FIG. 3 is a right side elevation view thereof;

FIG. 4 is a left side elevation view thereof;

FIG. 5 is an enlarged view of detail "5" identified in FIG. 1; and,

FIG. 6 is an enlarged view of detail "6" identified in FIG. 2. The dash-dot-dot-broken lines in the figures illustrate portions of the trousers that form no part of the claimed design. The dash-dot-dot-broken lines in FIGS. 1, 2, 5 and 6 are for the purpose of illustrating the enlarged views indicators and form no part of the claimed design. The evenly spaced dash lines are used to illustrate the stitching and form a part of the claimed design.
